UNITED STATES PATENT OFFICE.

THOMAS A. COLLISON, OF MOUNT VERNON, ILLINOIS, ASSIGNOR TO MOUNT VERNON CAR MANUFACTURING COMPANY, OF MOUNT VERNON, ILLINOIS, A CORPORATION OF ILLINOIS.

CARLINE AND PROCESS OF MAKING THE SAME.

1,330,980.

Specification of Letters Patent.

Patented Feb. 17, 1920.

Application filed April 26, 1916. Serial No. 93,612.

To all whom it may concern:

Be it known that I, THOMAS A. COLLISON, a citizen of the United States of America, residing at the city of Mount Vernon, county of Jefferson, in the State of Illinois, have invented a certain new and useful Carline and Process of Making the Same, of which the following is such a full, clear, and exact description as will enable any one skilled in the art to which it appertains to make and use the same, reference being had to the accompanying drawings, forming part of this specification.

My invention relates to a carline and the process for making the same, and more particularly to a carline formed of a single piece of sheet metal, and to the process of forming such a carline with the least possible number of operations.

In the accompanying drawings, which illustrate one form of carline made in accordance with my invention, Figure 1 is a view showing the blank of which the carline is to be formed; Fig. 2 shows the same blank after the first operation of bending has been performed thereon; Fig. 3 shows the completed carline; Fig. 4 is an enlarged sectional view of one-half of the carline, together with some of the parts of a railway car to which the carline is to be applied; and Fig. 5 is an enlarged perspective view of one end of the carline.

Like marks of reference refer to similar parts in the several views of the drawings.

The first operation in forming my carline is to stamp out a blank like that shown in Fig. 1. The blank may be made of a sheet of steel or other suitable metal. This blank has a slot 10 formed therein, dividing the center of the blank into an upper part 11 and a lower part 12, which are preferably of the same width. The ends of the blank may be somewhat reduced in width as shown in the drawings, but this is not essential. Each end is provided with a pair of slots 13 and 14, dividing the ends into a long upper extension 15, a short lower extension 16, and a central extension 17.

After the blank has thus been formed, by means of a suitable die, a portion of the upper edge is turned over to form a flange 18, and a portion of the lower edge is turned over to form a flange 19, preferably extending in opposite direction from the flange 18 so as to form a Z-bar, as best shown in Fig. 5

of the drawing. At the same time that these flanges 18 and 19 are turned over the central projections 17 of the ends are turned over at right angles to the body of the carline to form fastening means for securing the carline in position.

After this operation has been performed the blank is heated and by means of suitable dies, while the blank is hot, the ends 15 and 16 are bent down, as best shown in Fig. 5 of the drawings, so as to form fastening means for the carline, and at the same time the two parts 11 and 12 of the carline are separated, the upper part 11 being elongated and bent to form a truss-member, while the lower part 12 is maintained as nearly as possible straight so as to form a tie-member. This operation completes the carline, except for fastening in position a strut 20, extending between the members 11 and 12 at the center of the carline. The turned over ends 15 and 17 are provided with holes 21 for the passage of a bolt 22 which secures the same to the side plate 23 of a car. The overturned end 16 is also provided with an opening 24 adapted to receive a bolt 25, the same passing through the side plate 23 of the car. The carline may be also provided with suitable bolt holes 26 for securing the purlins 27 in position, and also for securing the filler-block 28 in position when a filler-block is used.

By forming my carline of a single piece of sheet metal I am enabled not only to form the article with the minimum number of operations, but also to increase the strength of the carline. It will be obvious that when knee-irons are riveted to the body of the carline, the entire carline can be no stronger than the rivets securing the pieces together. Another object which I obtain by forming my carline of a single piece is that by so forming the carline the distance between the ends of the carline can be made more uniform than where the carline is built up of a number of separate pieces.

Having fully described my invention, what I claim as new and desire to secure by Letters Patent of the United States is:

1. The process of making a carline which comprises forming a longitudinal slit in a flat blank of metal, bending the edges of said blank to the right and left to produce oppositely projecting flanges, heating the blank, separating the parts of the blank to

form truss and tie members, and bending the ends of the blank to form knee-irons.

2. The process of making a carline which comprises forming a longitudinal central slit and two pairs of end slits in a flat blank of metal, bending the edges of said blank to the right and left to form oppositely projecting flanges, heating the blank, separating the parts of the blank to form truss and tie members, bending the horizontal portions of the ends downwardly to form fastening means, and bending the perpendicular portion of the ends laterally under the upper horizontal portion to form additional fastening means.

3. A carline of Z-cross section having an

extension of its upper horizontal flange adapted to extend across the side plate of a car, a downward projection carried by said extension, a turned over portion of the vertical flange extending under the upper horizontal flange and adapted to bear on the side plate of the car opposite said downward projection and forming fastening means for securing the carline in position and a downward projection of the lower horizontal flange adapted to form additional means for securing the carline in position. 20 25

In testimony whereof, I have hereunto set my hand and affixed my seal.

THOMAS A. COLLISON. [L.S.]
